UNITED STATES PATENT OFFICE.

HENRY FLAD, OF ST. LOUIS, MISSOURI.

AIR-FILTER.

SPECIFICATION forming part of Letters Patent No. 296,548, dated April 8, 1884.

Application filed June 14, 1883. (No model.)

To all whom it may concern:

Be it known that I, HENRY FLAD, of St. Louis, in the county of St. Louis and State of Missouri, have invented certain new and useful Improvements in Air-Filters; and I do hereby declare the following to be a full, clear, and exact description of the invention, such as will enable others skilled in the art to which it appertains to make and use the same.

10 The object of this invention is to prevent dust and other solid matter from entering air-pumps and other pneumatic cylinders or chambers through their induction ports or passages, the invention being particularly designed for 15 use in connection with the air pumps and cylinders employed for operating the brakes of railway-cars, according to an invention described in an application for patent for improvement in electric air-brakes, filed by me 20 June 7, 1883. In said application I have shown and described brake-operating cylinders within which are nicely-fitted valves, the faces and bearings of which would be liable to injury from dust and cinder which pervade the air 25 in the vicinity of railway-trains, and more or less of which would enter the brake-cylinder were not means for intercepting it provided.

Figure 1 is a rear view of a locomotive-cab provided with an air-filter connected with an 30 air-pump used for supplying air in the ordinary manner for operating car-brakes, the roof of the cab and parts composing the filter being shown in section. Fig. 2 is a section in plane indicated by the line $x x$ of Fig. 1.

35 Referring to Fig. 1, the letter A designates the roof of the cab, and a short distance below it is a light partition, B. This partition B, roof A, side walls, C C, and end walls, C' C', inclose a chamber in which are stretched two 40 horizontal reticulated screens, D D, preferably of wire net-work, separated from each

other by an intervening space of, in practice, about four or five inches depth. The edges of the screens are secured to suitable cleats, e e, and the space between said screens is filled 45 with fibrous material, preferably raw cotton, as shown at F, which, in connection with the screens, forms a filtering-diaphragm through which air may pass, but which will intercept dust, cinder, and other solid matter. 50

In the side walls, C C, above the screens, are formed air-passages g g, through which the external air may enter under the roof, and from an opening in the partition B under the screens a pipe, H, leads to the induction port 55 or passage of the air-pump I. It will now be seen that when the pump is operated and exerts suction through the pipe H the air which enters the openings g will be drawn through the screens and interposed cotton, 60 and will thus be filtered in its passage to the portion of the chamber below the screens and to the pipe H, through which it passes to the pump, so that only clean air will be supplied by the pump to the pipes and brake-cylinders. 65

What I claim is—

The combination, with an air-pump located in the locomotive-cab, of the air-filter arranged in a chamber directly under the roof of the 70 cab, said chamber being provided with openings at one side of said filter, and the suction-pipe leading from said chamber on the opposite side of the filter to the air-pump, substantially as described. 75

In testimony whereof I have signed this specification in the presence of two subscribing witnesses.

HENRY FLAD.

Witnesses:

A. B. METCALFE,
FRITZ HÖPPNER.
